UNITED STATES PATENT OFFICE.

BERT N. PARRISH, OF JACKSON, MICHIGAN, ASSIGNEE TO ELECTRIC INTAKE HEATER COMPANY, OF JACKSON, MICHIGAN, A CORPORATION OF MICHIGAN.

HEATER FOR INTAKE-MANIFOLDS OF INTERNAL-COMBUSTION ENGINES.

1,260,441.

Specification of Letters Patent. Patented Mar. 26, 1918.

Application filed May 28, 1917. Serial No. 171,473.

To all whom it may concern:

Be it known that I, BERT N. PARRISH, a citizen of the United States, residing at the city and county of Jackson and State of Michigan, have invented certain new and useful Improvements in Heaters for Intake-Manifolds of Internal-Combustion Engines, of which the following is a specification.

This invention relates to improvements in heaters for intake manifolds of internal combustion engines.

The objects of the invention are:

First, to provide a heater for the intake manifold of internal combustion engines which is simple in structure and economical to manufacture.

Second, to provide a heater for the manifold of internal combustion engines in which the heat generated is efficiently transmitted to the walls of the manifold.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a side elevation of a portion of the intake manifold for an internal combustion engine showing the manner of applying my invention thereto and the connections therefor, together with a controlling switch on the dash of an automobile.

Fig. II is an enlarged detail section taken on a line corresponding to line 2—2 of Fig. I.

Fig. III is an enlarged detail section taken on a line corresponding to line 3—3 of Fig. II.

Fig. IV is a bottom view of the heating element employed in my heater, the lower sheet of insulation being removed.

Fig. V is a diagram showing the connections between the heating elements of my heater, the source of current and the switch.

In the drawing, similar reference characters refer to similar parts throughout the several views, and the sectional views are taken looking in the direction of the little arrows at the ends of the section lines.

Referring to the drawing, the reference

character 1 indicates a portion of the intake manifold of an internal combustion engine. In practice I prefer to thicken the walls of the conduit which leads from the carbureter as indicated at 2 to provide walls of sufficient thickness to allow the forming of recesses therein for receiving the heating elements. As shown in Figs. II and III these recesses 3 as illustrated extend lengthwise of the intake conduit 4 and are substantially rectangular in outline and provided with flat bottoms.

The heating element comprises the cover plate 5, the top insulation 6, the resistance element 7 and the bottom insulation 8. Binding posts 9 are secured to each end of the resistance element and project through suitable apertures in the top insulation and the cover plate. The end of the resistance element, the top insulation and the cover plate are clamped together by means of the nuts 10 and the binding post 9, an insulating washer 10' being interposed between the nut 10 and the cover plate 5. The ends of the cover plate extend beyond the adjacent ends of the heating element and are secured to the manifold by means of the screws 11.

The connections for my improved heater are diagrammatically illustrated in Fig. V in which the reference character H indicates the two heating elements on the opposite sides of the manifold and the reference S indicates the source of current which, as shown, is connected in series with the two heating elements and adapted to be disconnected therefrom by a switch 12 which, as shown in Fig. I, may be mounted upon the dash or any other suitable part of the car.

The operation of my improved heater will be readily understood from the above description. When it is desired to start a car equipped with my heater it is merely necessary to close the switch 12 whereupon the heat generated in the resistance element 7 will be transmitted to the walls of the intake manifold and heat the same sufficiently so that the fuel in the charges drawn therethrough is effectively vaporized thereby expediting the starting of the motor. By placing the heating element in recesses in the walls of the manifold I obtain an efficient transmission, or transfer of heat, from the heating elements to the walls of the intake manifold and there is not so great an opportunity for the radiation of heat as

there is in those devices in which the heating elements are merely strapped or otherwise secured to the outside of the walls of the intake manifold. My invention may be applied to an ordinary intake, where the walls thereof are not sufficiently thick to admit of the formation of recesses therein, by building up the walls of the intake manifold by means of aluminum or other suitable metal.

Having thus described my invention, what I claim as new and desire to secure by Letters Patent, is:

1. In a structure of the class described, the combination with an intake manifold of an internal combustion engine having thickened walls with recesses therein, of heating elements secured in said recesses and each comprising an electric resistance element and a cover plate, means for insulating said resistance element from said cover plate and from the walls of said recess, binding posts for the ends of said heating element extending through said cover plate, and means for securing said cover plate in said recess.
2. In a structure of the class described, the combination with an intake manifold of an internal combustion engine having a flattened recess in the wall thereof, of a heating element secured in said recess and comprising a resistance element and a cover

plate, means for insulating said resistance element from said cover plate and the walls of said recess, means for securing said cover plate to said manifold, and binding posts for the ends of said resistance element projecting through said cover plate.

3. In a structure of the class described, the combination with an intake manifold having a recess in the wall thereof and extending but partially therearound, of a flat heating element secured in said recess and insulated from the walls thereof, the said heating element comprising an insulated resistance element, and means for connecting said resistance element to a source of electricity.

4. In a structure of the class described, the combination with an intake manifold having a recess in the wall thereof, of a laterally removable flat heating element secured in said recess and insulated from the walls thereof, said heating element comprising an insulated resistance element.

In witness whereof, I have hereunto set my hand and seal in the presence of two witnesses.

BERT N. PARRISH. [u.s.]
